UNITED STATES PATENT OFFICE.

FRANK GARACA, OF BESSEMER, ALABAMA.

SPARK-PLUG.

1,266,009.

Specification of Letters Patent. Patented May 14, 1918.

Application filed June 20, 1917. Serial No. 175,914.

To all whom it may concern:

Be it known that I, FRANK GARACA, a citizen of the United States, residing at Bessemer, in the county of Jefferson and State 5 of Alabama, have invented certain new and useful Improvements in Spark-Plugs, of which the following is a specification.

This invention relates to new and useful improvements in spark plugs and the principal object of the invention is to provide 10 means for adjusting the distance apart of the electrodes.

Another object of the invention is to provide spring means engaging one of the electrodes and tending to force the same toward 15 the other electrode.

A further object of the invention is to provide means for moving the electrode longitudinally to compress or expand the 20 spring.

Another object of the invention is to provide a device of this character, which is simple and durable in construction, reliable and efficient in operation and one which 25 can be manufactured and placed upon the market at a minimum cost.

The invention also consists in certain other features of construction and in the combination and arrangement of the several parts, to be hereinafter fully described, 30 illustrated in the accompanying drawings and specifically pointed out in the appended claims.

In describing my invention in detail, reference will be had to the accompanying drawings, wherein like characters denote like or corresponding parts throughout the several views, and in which:

The figure represents a longitudinal sectional view through the spark plug.

In this figure, 1 represents the outer metal shell of the plug provided with the usual screw threaded lower end for engaging with the screw threaded hole in the cylinder top. 2 represents the porcelain body held in the shell by means of the packing nut 3. 4 represents a movable electrode which is in the form of a rod passing longitudinally through the body 2 and provided with 45 the screw threaded upper end which is adapted to receive the nut 5 and the binding

tap 6. The lower end of the rod 4 is provided with a collar 7 and a coil spring 8 surrounds the rod and bears against this collar, the porcelain body 2 having a recess 9 in its lower end for receiving said spring and collar. A washer 10 fits in the bottom of this recess and has an opening therein through which the rod 4 passes. The spring is compressed between this washer and the 55 collar 7 and tends to force said collar and the rod downwardly, but this movement is prevented by the nut 5 engaging the top of the body 2, so that by adjusting this nut the 60 position of said rod may be regulated. 11 65 indicates the stationary electrode secured to the lower end of the shell 1 as usual.

It will be seen that the spring tends to move the end of rod 4 into contact with the end of the electrode 11 so that the space between the electrodes is adjusted by means 70 of the nut 5.

It is thought from the foregoing that the advantages and novel features of my invention will be readily apparent.

I desire it to be understood that I may make slight changes in the construction and in the combination and arrangement of the several parts, provided that such changes fall within the scope of the appended 75 80 claims.

I claim as my invention:

1. A spark plug comprising a shell, a porcelain body secured therein and having a recess in its lower end, stationary and movable electrodes, means for adjusting the movable electrode, with relation to the stationary electrode, and yieldable means associated with said movable electrode and adapted to be arranged in said recess.

2. A spark plug comprising a stationary and movable electrode, said movable electrode consisting of a rod passing through the body of the plug, said rod having a screw threaded upper end, a nut engaging 95 said end and bearing against the top of the plug, a collar on the lower end of said rod and a spring compressed between said collar and a part of the plug.

3. A spark plug comprising a shell and a 100 porcelain body held therein, said body having a recess in its lower end, stationary and

movable electrodes, said movable electrodes consisting of a rod passing through the body and through said recess, said rod having a screw threaded upper end, a nut engaging with said upper end, a collar on said rod and a coil spring in the recess and engaging said collar.

In testimony whereof I affix my signature in presence of two witnesses.

FRANK GARACA.
